His Attorney.

UNITED STATES PATENT OFFICE.

HENRY V. DEEMAR, OF ST. LOUIS, MISSOURI, ASSIGNOR TO JOHN H. BRUNINGA,
TRUSTEE, OF ST. LOUIS, MISSOURI.

HEATER.

Application filed May 31, 1924. Serial No. 716,986.

This invention relates to heaters, and more particularly to heaters which may operate with gas fuel and the like for heating rooms or buildings.

5 One of the objects of this invention is to provide a heater which will be economical in the matter of fuel consumption and which may provide a positive air circulation therethrough for heating the air.

10 Another object is to provide such a heater of novel design which may be adapted to heat a considerable quantity of air in a short time.

Another object is to provide such a heater 15 in which a considerable extent of heating surface may be heated by a single flame and which heating surface is brought into intimate contact with the air to be heated.

Further objects will appear from the detail description taken in connection with the accompanying drawing, in which:

Figure 1 is a vertical section showing a heater embodying this invention;

Figure 2 is a section on line 2—2, Figure 25 1;

Figure 3 is a section on line 3—3, Figure 1; and

Figure 4 is a fragmentary view showing another embodiment of this invention.

30 Referring to the accompanying drawing, 1 designates a central air tube which is surrounded by a second tube 2 forming therebetween an annular combustion chamber 3. These tubes may be constructed of suitable 35 sheet metal and supported relatively to one another as will presently be pointed out.

The tube 1 fits at its lower end into a casting 4 provided with a rim or flange 5 adapted to receive the tube 2 and properly 40 space the same from the tube 1. The casting 4 is further provided with an outer flange 6 spaced from the flange 5 by suitable webs 7 and providing between them and the flange 5 a chamber 8 communicating through 45 suitable openings 9 with the interior of the tube 1. The lower end of the tube 1 below the casting 4 is adapted to be connected to the outlet tube 10 of a suitable fan or blower 11.

50 The casting 4 may be provided with a connection 12 suitable for attachment with a suitable mixer 13 for supplying a mixture of air and gas to the combustion chamber 3. A suitable pilot 14 may also be connected 55 with the gas supply and arranged for ig-

niting the gas in the combustion chamber. A series of air supply tubes 15 is mounted in the casting 4 so as to pass through the chamber 8 and extend a substantial distance into the combustion chamber 3. These tubes 60 are annularly arranged as shown in Figure 3 and serve to supply air to the combustion chamber. The mixer 13 may be such as described in Patent No. 1,341,266, granted May 25, 1920.

65 The gas mixture entering at the connection 12 is ignited within the chamber 3 and burns with the flame which travels upwardly along said chamber. The mixture as supplied by the mixer 13 comprises a certain proportion of air sufficient to cause combustion. The tubes 15, however, supply an additional quantity of air at the point where combustion begins or at the origin of the flame. This point is beyond the point of 70 entrance of the combustible mixture. Thus the flame is supplied at its origin with a plentiful quantity of air so that a rapid combustion is promoted and a long flame produced. This flame travels upwardly 75 along the chamber 3 to practically the full extent of said chamber, heating the tubes 1 and 2 to a high temperature.

80 The upper end of the combustion chamber 3 is closed by a plate 16 provided with a flange 17 to receive the tube 1 and an outer flange 18 to receive the tube 2 in order to properly space the tubes from one another.

85 The plate is perforated with an annular series of perforations into each of which a short tube 19 is spun. The upper ends of the tubes 19 are similarly spun into perforations in the lower plate 20 of a hood 21 adapted for connection with a suitable flue 22. A damper 23 may be supplied in the flue 22 if desired. Passage is thus provided 90 for the burnt gases from the chamber 3 through the tubes 19 to the hood 21, thence to the flue 22.

95 The outer flange 6 of the casting 4 may be provided with a shoulder adapted to receive an outer tube 24 surrounding the tube 2 and providing an air jacket therearound. The upper end of the tube 24 terminates in a flared lip 25 just below the plate 16 and is spaced from the tube 2 by a series of wings 26 formed on the flange 18 but having spaces therebetween to permit the passage 100 of air out of the tube 24. The outward flare of the lip 25 provides a horizontally 105 110

directed outlet for the jacket 24 just beneath the plate 16. An atomizer nozzle 27 connected with a suitable moisture supply 28 is mounted in the lower end of the tube 1.

5 In the operation of this heater, before the flame has been started the blower 11 is set into operation so as to blow air upwardly through the tube 1. This air passes out at the outlet from beneath the hood 21 by the 10 spaces between the tubes 19. Thus an ample supply of air is passed upwardly through the tube 1 so as to keep the same from overheating, and the air thus heated passes outwardly in a horizontal direction between the pipes 19 and below the lower plate 20. A certain amount of the air supplied by the blower 11 also finds its way through the openings 9 and upwardly within the jacket 24 and out at the upper outlet thereof, also 15 in a horizontal direction. This serves to take up the heat of the outer tube 2 so as to prevent overheating thereof. The horizontal outward flow of the air from between the tubes 19 also tends to create a suction 20 at the outlet of the jacket 24 so as to assist in providing a draft of air through said jacket. Thus an ample quantity of air is passed through the heater and over the heating surfaces and rapidly discharged into 25 the room. The upward draft of air in the tube 1 serves to operate the atomizer nozzle 27 so as to supply a suitable quantity of moisture to the heated air.

35 In the embodiment shown in Figure 4 a simple ring 29 is provided in place of the casting 4 and the tubes 15 are mounted in said ring. The jacket 24 is spaced from the tube 2 by means of a series of spacers 30 fixed to the tube in any suitable manner 40 as by means of the screws 31. The connection 12 is mounted in the tubes 2 and 24. This embodiment operates in the same manner as that previously described, but in this case the draft of air through the jacket 45 24 is set up by induction rather than the pressure of the blower.

50 It will be evident, therefore, that this invention provides a simple and effective heater in which a burner is provided which will heat the entire length of the tubes 1 and 2 and which is provided with an ample draft of air passing over these tubes so as to take up the heat therefrom and prevent their overheating. By means of such a heater a 55 large quantity of air can be heated in a comparatively short time since the heating surfaces may be operated at a higher temperature than when only natural draft is depended upon for circulation.

60 It is obvious that various changes may be made in details of construction without departing from the spirit of this invention; it is, therefore, to be understood that this invention is not to be limited to the specific 65 details shown and described.

Having thus described the invention, what is claimed is:

1. A heater comprising, a casing adapted to form an annular chamber, means for supplying a combustible mixture to said chamber, and ducts entering and extending into said chamber and adapted to admit air into the flame beyond the entrance of the combustible mixture.

2. A heater comprising, a casing adapted to form an annular chamber, means for supplying a combustible mixture to the bottom of said chamber, and tubes entering the bottom of and extending up into said chamber and adapted to admit air into the flame above the point of entrance of said supplying means.

3. A heater comprising, a casing adapted to form an annular combustion chamber, means for supplying a combustible mixture to said chamber at one end thereof, and a series of air ducts extending into and directed along said chamber and terminating beyond the point of entrance of said supplying means, adapted to deliver air to the flame beyond said point of entrance.

4. A heater comprising, a casing adapted to form an annular combustion chamber, means for supplying a combustible mixture to said chamber at one end thereof, and a series of air ducts extending into and directed along said chamber and terminating beyond the point of entrance of said supplying means, the mouths of said ducts forming points of origin for the flame.

5. A heater comprising, a vertical air tube surrounded by a casing to form an annular combustion chamber, means for supplying a combustible mixture to the bottom of said chamber, and ducts entering the bottom of and extending upwardly into said chamber and adapted to admit air into the flame at its origin.

6. A heater comprising, a vertical air tube surrounded by a casing to form an annular combustion chamber, means for supplying a combustible mixture to the bottom of said chamber, ducts entering the bottom of and extending into said chamber and adapted to admit air into the flame at its origin, and means for forcing air through said tube.

7. A heater comprising, a vertical air tube surrounded by a casing to form an annular combustion chamber, means for supplying a combustible mixture to the bottom of said chamber, ducts entering the bottom of and extending into said chamber and adapted to admit air into the flame at a point beyond the entrance of the combustible mixture, an air jacket surrounding said casing, and means for forcing air through said tube and said jacket.

8. A heater comprising, a vertical tube having an air inlet at one end and an air outlet at its other end, a casing surround-

ing said tube to form an annular combustion chamber, and a blower for forcing air through said tube in order to prevent overheating of the tube.

5. 9. A heater comprising, a vertical tube having an air inlet at one end and an air outlet at its other end, a casing surrounding said tube to form an annular combustion chamber, an open air jacket surrounding said 10 casing, and a blower adapted for forcing air through said tube and said jacket to prevent overheating of said casing.

10. 10. A heater comprising, a tube surrounded by a casing to form an annular chamber, means for supplying a combustible mixture to said chamber, and a series of 15

tubes annularly arranged and adapted to connect said chamber with a flue, the spaces between said tubes providing an outlet for said tube.

20

11. A heater comprising, a casing adapted to form an annular chamber, means for supplying a combustible mixture to the lower part of said chamber, and ducts entering said chamber and terminating above the bottom 25 thereof adapted to supply air to the flame at its origin above the bottom of said chamber.

In testimony whereof I affix my signature this 25th day of April, 1924.

HENRY V. DEEMAR.
